United States Patent Office.

SAMUEL HUNTER, OF ANDREW COUNTY, MISSOURI.

Letters Patent No. 83,856, dated November 10, 1868.

IMPROVEMENT IN SAWING-MACHINES.

The Schedule referred to in these Letters Patent and making part of the same

To all whom it may concern:

Be it known that I, SAMUEL HUNTER, of Andrew county, in the State of Missouri, have invented a new and useful Improvement in Sawing-Machines; and I do hereby declare that the following is a full, clear, and exact description of the same, reference being had to the accompanying drawings, and letters of reference marked thereon, making a part of this specification, in which—

Figure 1 is a front elevation;

Figure 2 is a plan view;

Figure 3 is an elevation of the side on which is the saw-gearing; and

Figure 4 is a rear elevation.

To enable those skilled in the art to make and use my invention, I now proceed to describe its construction and operation.

Similar letters in the drawings refer to like parts.

This invention relates to a portable machine for sawing logs, at the places where they are felled, crosswise into bolts, blocks, cord-wood, &c., or, by adjusting the saw in a vertical position, lengthwise, into boards, plank, or the like; and it consists in adjusting a peculiar and novel horse-power to the frame-work supporting the machinery; also in adapting a peculiar and novel belt-tightener to the same; and also in adapting the gearing, by means of which the saw is moved, to an adjustable gate, to which said saw is attached, as will herein-after more fully appear.

In the drawings, A represents a substantial frame-work, mounted upon a stout carriage, B, by means of which latter the frame, with its machinery of various kinds, is transported from place to place. Upon the front part of the carriage B are two semicircular plates, a a', projecting forward, the lower plate a being supported at its centre upon the front cross-bar of the carriage, and attached at each end to the lower ends of the forward uprights b b' of the frame-work, the upper plate a' resting upon the lower plate, edge to edge, and pivoted at its extremities to the uprights b, so as to be capable of being raised upon its said pivots. Semi-circular notches, c, are cut at suitable points along the upper edge of the plate a, and similar notches, c', at corresponding points along the lower edge of the plate a', each pair of notches c and c' forming, when the upper plate is shut down upon the lower, circular holes, in either of which may be placed the shaft d of the horse-power, the inner end of said shaft being secured in a pivoted upright, so that the shaft may be rotated around this upright as a centre, and transferred from one hole of the plate a a' to another at pleasure, according to the direction it may be found convenient to give it, in forests and similar places, where the machinery is more especially designed to be put in operation.

The shaft d is connected, by bevel-gearing, with a

vertical shaft, e, held upright by a suitable bracket on the front upper cross-bar h of the frame-work. To the upper end of the shaft e is attached the horizontal sheave e', provided with a number of belt-seats. Over the sheave e' is the driver's seat, i.

To the right-hand side of the frame-work A is secured a vertical shaft, k, square or polygonal in cross-section, on the upper end of which is a pulley, k'; to receive the belt from the upper seat of the sheave e'. The shaft k passes through the spur-gear k", which slides upon said shaft, being supported at one side by the spur-gear l, and at the other side upon the ends of the arms l, projecting beneath the spur-gear l from the end of the gate m, which also sustains the said spur-gear l. The gearing k' and l imparts the motion derived by belt from the main sheave e', by means of a crank, m', to a connecting-rod, m", joined at its opposite extremity to the saw n. The gate m is supported upon two vertical screws, m" m'", placed in the near end of the frame-work, by means of which screws, which receive simultaneous rotation, in the same direction, through the agency of the connecting spur-gear o, the gate is moved up or down as occasion may require, as in cutting through a log, or withdrawing from the same. The upper end of the screws is provided with sheaves r r', round either or both of which the belt may be passed to assist in the operation.

On the top of the frame-work is a horizontal guide-way, s, stretching crosswise half way, more or less, of the frame. Within the guide-way slides a bar, s', provided at its outer end with a handle, s", and notched for a suitable distance upon its upper side, and pivoted at its inner end to or near the centre of a bar, t, the forward extremity of which is pivoted to the front upper cross-beam of the frame-work A, and to the rear extremity of which is attached an upright roller, t'. To the guide-way is pivoted a pawl, s', which is arranged to catch in the notches in the upper side of the bar s', where a lever, u, pivoted to a side beam of the frame, nearly under the said bar s', is brought down so as to bring its eccentric-head, u', under the bar s', and so elevate it against the pawl s'. When the bar s' is thus elevated, it cannot be slid in or out, and is thus in a condition efficiently to aid the roller t' in the discharge of its function of a belt-tightener.

Having thus described my invention,

What I claim as new, and desire to secure by Letters Patent, is—

The plates a a', the lower rigid, the upper pivoted, provided with the orifices c c', adapted to varying the direction of the driving-shaft, substantially as described.

SAMUEL HUNTER.
